UNITED STATES PATENT OFFICE.

EDMUND E. SCHRAM, OF DETROIT, MICHIGAN.

PORTABLE INDICATOR.

1,241,771.

Specification of Letters Patent.

Patented Oct. 2, 1917.

Application filed November 15, 1916. Serial No. 131,376.

To all whom it may concern:

Be it known that I, EDMUND E. SCHRAM, a citizen of the United States of America, residing at Detroit, in the county of Wayne 5 and State of Michigan, have invented certain new and useful Improvements in Portable Indicators, of which the following is a specification, reference being had therein to the accompanying drawings.

10 This invention relates to a portable indicator, and the primary object of my invention is to provide a novel electric indicating device that may be advantageously used by ushers in moving picture houses, darkened 15 theaters or other places to signal the number of vacant seats, so that persons standing in the rear of an audience may be readily seated.

A further object of my invention is to 20 combine a flashlight and exhibitor in such a manner that the flash light may be used to illuminate the exhibitor or may be used for searching or observation purposes in dark places, for instance by a theater usher 25 attempting to recover a lost article in a dark aisle or about a seat.

Another object of my invention is to provide a portable indicator consisting of comparatively few parts that are easy to assemble and manipulate, durable and inexpensive to manufacture and highly efficient for the purposes for which it is intended.

With these and other objects in view, my invention resides in the novel construction, 35 combination and arrangement of parts to be hereinafter specifically described and then claimed.

Reference will now be had to the drawings, wherein

40 Figure 1 is a perspective view of a preferred form of portable indicator;

Fig. 2 is a horizontal sectional view of the exhibitor thereof;

Fig. 3 is a vertical sectional view of the 45 exhibitor;

Fig. 4 is a perspective view of a modified form of indicator;

Fig. 5 is a similar view of a further modified form of indicator, and

50 Fig. 6 is an elevation of a stanchion device provided with the indicator.

Reference will first be had to Figs. 1 to 3 inclusive showing the preferred form of device, and the reference numeral 1 generally 55 denotes a portable source of electrical en-

ergy, as an ordinary flashlight including a casing for a storage battery, a button or switch 2 for controlling the operation of the flashlight, a holder 3 for a reflector and socket member 4, and an incandescent lamp 60 5 supported by the reflector and socket member. These elements are of a form common in many flashlights and I intend to use the flashlight as a convenient source of electrical energy for its usual purposes, besides 65 illuminating an exhibitor as an indicator.

On the holder 3 of the flashlight 1 is a rotatable support 6 which is preferably knurled or roughened whereby it may be easily revolved. The support 6 is provided 70 with a rectangular casing 7 having a hinged lid 8 adapted to be opened when it is desired to use the flashlight 1 for searching or observation purposes in dark places.

The side walls of the casing 3 are provided with openings 9 and normally closing said openings are transparent plates 10 made of glass, celluloid or other material and suitably held against the inner sides of the casing walls. The transparent plates 10 75 have clear or frosted portions 11 representing numerals, for instance, 1 to 4 as the casing 7 is rectangular and presents four walls. The remaining portions of the transparent plates 10 have a dark back ground for the 80 numerals 1 to 4, so that said numerals will be prominently displayed when the interior 85 of the casing 7 is illuminated by the flashlight.

In the casing 7 is a stationary cylindrical 90 wall or member 12 that may be supported by the reflector 4 in order that the casing 7 may be rotated, and the wall or member 12 has an opening 13 at one side thereof, thus concentrating the rays of light at said opening 95 and cutting off all the numerals except that one in alignment with the opening 13. As shown in Fig. 3, the numeral 2 will be illuminated and the numerals 1, 3 and 4 100 shut off from the rays of light emitted by the lamp 5.

In Fig. 4, there is illustrated a combined flashlight and exhibitor, and the exhibitor casing 14 has a display opening 15 and a slide 16. The slide 16 is somewhat in the 105 form of a stencil and by shifting the same in the casing 14 a desired numeral or designation may be illuminated by the flashlight.

A further modification is shown in Fig. 5 wherein a flashlight 17 has a large circular 110

head 18 provided with indicia and matter on the head 18 may be displayed by rotating a shutter 19.

5 A rotatable exhibitor 20 is shown in Fig. 6 as supported by a stanchion or stand 21. This stanchion may have a source of electrical energy located in the base thereof, or accommodate lead-in wires from a remote source of electrical energy.

10 As mentioned in the beginning I have designed a portable indicator particularly for the ushers of darkened theaters, for instance, where moving pictures are shown and the audience is constantly changing. 15 In such amusement places the popularity of a film taxes the seating capacity of the place and patrons are often caused to stand until seats are vacated. It is the present practice for ushers to run the aisles or indicate by 20 the fingers the number of vacant seats, and to eliminate this practice and annoyance to the audience, my device may be silently used by an usher to flash a number or indicia which will indicate to the patrons 25 standing in the rear of the audience the number of vacant seats in the front part of the theater. It is only necessary for the usher to adjust the device to display the desired number or indicia and then operate the 30 flashlight. By properly holding the device a vacant seat may be indicated without annoyance to the audience, and as a result of such use, patrons are better satisfied and the

profits of the play house materially increased.

While in the drawings there are illustrated the preferred embodiments of my invention, it is to be understood that the structural elements are susceptible to such changes in size, shape and manner of assemblage, as fall within the scope of the appended claims.

What I claim is:—

1. The combination of a flash light and an exhibitor rotatable on the outer end 45 thereof about the longitudinal axis of the flash light and having sign displaying walls. 2. The combination of a flash light having a lamp axially of the outer end thereof, an exhibitor rotatable on the outer end of 50 said flash light about the longitudinal axis thereof, and a lid on the outer end of said exhibitor adapted to be opened to emit rays of light from the lamp of said flash light.

3. A portable indicator comprising a flash 55 light, a holder at the outer end thereof, an exhibitor rotatable on said holder about the longitudinal axis of said flash light and provided with sign displaying walls, and a lid closing the outer end of the exhibitor.

In testimony whereof I affix my signature in the presence of two witnesses.

EDMUND E. SCHRAM.
